UNITED STATES PATENT OFFICE.

JOSEPH CHARLES AUGUSTE LABRECHE, OF MONTREAL, QUEBEC, CANADA.

SMOKING-PIPE.

1,261,038.

Specification of Letters Patent. Patented Apr. 2, 1918.

Application filed June 8, 1917. Serial No. 173,587.

To all whom it may concern:

Be it known that I, JOSEPH CHARLES AUGUSTE LABRECHE, a subject of the King of Great Britain, residing at 419 Viger street, in the city of Montreal, in the Province of Quebec, in the Dominion of Canada, have invented certain new and useful Improvements in Smoking-Pipes; and I do hereby declare that the following is a full, 10 clear, and exact description of the same.

The present invention relates to improvements in smoking pipes, to be hereinafter described, and in order to more clearly disclose the construction and operation and use 15 of the invention, reference should be had to the accompanying drawings forming part of the present application.

In the drawings, Figure 1 is a longitudinal section through the pipe.

20 Fig. 2 is a perspective view of the preferred form of the baffle which comprises the invention, and

Fig. 3 is a side view thereof.

25 Fig. 4 is a longitudinal section through the pipe, showing a modification of the invention.

Throughout the several figures of the drawings, like numerals of reference designate the same parts.

30 In the drawings, 1 is the bowl of the pipe, having the usual tubular stem section or neck 2, and 3 is the usual tubular stem which engages said neck 2 in any suitable manner, here shown as fitting snugly in said neck 2.

35 4 is a baffle member of unitary construction suitably disposed within the bore of the neck 2 and preferably consists of cylindrical sections 5, 6 and 7 united together by the flat webs 8 and 9, said webs being disposed 40 in a common plane which passes through the axis of the baffle.

The innermost cylindrical section 5 preferably has a semi-spherical head 10, and the outermost cylindrical section 7 is here illustrated with an inner thread 11 adapted to engage a corresponding thread on the end of the stem 3. The sections 5 and 6 are respectively provided with the channels 12 and 13, while the web 8 is provided with a 45 slot 14. The web 9 consists of two flat members, which are spaced apart to provide an opening or passage between them.

50 It will thus be seen that the smoke will enter the channel 12, pass through the slot 14, through the channel 13 and in between the two members of the web 9 and into

the tubular stem 3. In so doing, the heavier products, such as nicotin, of which the smoke is composed will collect in the chambers 15, 16 and 17, and when the smoke reaches the mouth of the smoker it will have been purified and deprived of nicotin. Therefore, the tobacco, which undoubtedly is drawn into the stem in the ordinary pipe, will be held within the compartments 15, 16 and 17, and thus prevented from blocking the stem or reaching the mouth of the smoker.

The neck 2, as illustrated in the drawings, has been considerably enlarged in order to 70 show the invention properly, but it is thought that the usual tubular opening will have to be very slightly enlarged. Moreover, the improved baffle is here shown as being threaded on the end of the stem 3; 75 but without departing from the spirit of the invention, it will be clearly seen that it can be made independent therefrom, or instead of using a thread, a snug connection would probably serve the purpose.

80 It is absolutely immaterial whether the number of sections is increased or even decreased. For instance, it may be convenient in some cases to eliminate the section 6 or to provide only one section with the web 8, 85 and this web 8 could be secured in any suitable way to the stem of the pipe or made independent therefrom.

The advantage of securing the baffle member 4 to the stem 3 is that in order to clean 90 the pipe the stem 3 fixedly connected to the member 4 is pulled out; but probably in some special pipe designs this would not be practicable, and the stem, therefore, could be made absolutely independent from the 95 member 4.

In cleaning the pipe illustrated in the drawings, all that is necessary to do is to pull out the stem 3 from the neck 2, which removes the baffle member 4 with it, and 100 clean the member 4 by any suitable means. In removing the member 4, all the dirt, nicotin and tobacco in the chambers 15, 16 and 17 will be pulled out at the same time.

The modification illustrated in Fig. 4 105 differs slightly from the preferred form disclosed in Fig. 2 in the flanged end 18 which overlaps the end of the pipe. The stem 3 may be screwed or otherwise secured to said end 18.

110 What I claim is:—

As a new article of manufacture, a baffle

device of unitary construction adapted to fit in the bore of the neck of a pipe and consisting of a plurality of cylindrical sections arranged in spaced, parallel relation transversely of said bore, and webs uniting the same and disposed in a plane passing through the axis of the baffle; each section excepting the outermost one being provided with a channel extending transversely across 10 its periphery, and each web being provided

with a slot, to permit the passage of the smoke therethrough, the outermost section having an axial smoke passage into which the slot in the adjacent web directly opens.

Signed at Montreal, Quebec, Canada, this 15
14th day of April, 1917.

JOSEPH CHARLES AUGUSTE LABRECHE.
